UNITED STATES PATENT OFFICE.

EDWARD ALLEN THOMPSON, OF CLOVERDALE, CALIFORNIA.

DESIGN FOR A FILE-CABINET.

45,359.

Specification for Design.

Patented Mar. 3, 1914.

Application filed December 17, 1913. Serial No. 807,353. Term of patent 14 years.

To all whom it may concern:

Be it known that I, EDWARD A. THOMPSON, a citizen of the United States, residing at Cloverdale, in the county of Sonoma and State of California, have invented a new, original, and ornamental Design for File-Cabinets, of which the following is a specification, reference being had to the accompanying drawing, forming part thereof.

The figure is a perspective view of the file cabinet complete showing my new design.

I claim:

The ornamental design for a file cabinet as shown.

EDWARD ALLEN THOMPSON.

Witnesses:

CHARLES A. EDWARDS,
ISAAC S. LEWIS.
